(57) **CLAIM**

The ornamental design for a portable electronic device, as shown and described.

DESCRIPTION

FIG. 1 is a front perspective view of a first embodiment of a portable electronic device in accordance with our new design, wherein a retractable camera of the portable electronic device shown in solid lines is in an extended position; FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is another front perspective view thereof when the retractable camera shown in solid lines is in a retracted position;

FIG. 9 is a front perspective view of a second embodiment of a portable electronic device in accordance with our new design, wherein a retractable camera of the portable electronic device shown in solid lines is in an extended position;

FIG. 10 is a front view thereof;

FIG. 11 is a rear view thereof;

FIG. 12 is a left side view thereof;

FIG. 13 is a right side view thereof;

FIG. 14 is a top plan view thereof;

FIG. 15 is a bottom plan view thereof;

FIG. 16 is another front perspective view thereof when the retractable camera shown in solid lines is in a retracted position;

FIG. 17 is a front perspective view of a third embodiment of a portable electronic device in accordance with our new design, wherein a retractable camera of the portable electronic device shown in solid lines is in an extended position;

FIG. 18 is a front view thereof;

FIG. 19 is a rear view thereof;

FIG. 20 is a left side view thereof;

FIG. 21 is a right side view thereof;

(Continued)

FIG. 22 is a top plan view thereof;
 FIG. 23 is a bottom plan view thereof; and,
 FIG. 24 is another front perspective view thereof when the retractable camera shown in solid lines is in a retracted position.
 The broken lines, which show portions of the portable electronic device, form no part of the claimed design. The dot dash lines in the figures surrounding the retractable camera shown in solid lines represent an unclaimed boundary line and form no part of the claimed design.
